UNITED STATES PATENT OFFICE

WES W. MCCAIN, OF OAK PARK, ILLINOIS, ASSIGNOR TO BLUE VALLEY CREAMERY COMPANY, OF CHICAGO, ILLINOIS, A CORPORATION OF DELAWARE

PERFORATING DEVICE

Application filed July 16, 1927. Serial No. 206,295.

This invention relates to perforating devices for use in conjunction with wrapping machines for making some mark of identification on the wrapper so that the time and place of wrapping may be readily determined.

The invention may be applied to any kind of wrapping machine but it has been designed primarily for use with butter wrapping machines. Print butter is usually wrapped first in parchment paper or web, then in paraffin web and then it is enclosed within a cardboard carton. Ordinarily a creamery desires information as to when and at what plant the butter has been churned so that if a purchaser criticizes the butter for any reason it is possible to trace the time of packing, the batch from which the butter was churned, and the plant at which the butter was churned. A preferred way to get this information is to mark one of the wrappers with certain symbols or numbers so that the information can be readily ascertained.

Usually the purchaser discards the outer carton and the paraffin wrapper but invariably retains the first wrapper on the butter until the butter has been used. The proper wrapper to bear the identification is the first or parchment wrapper. Various methods may be employed to mark this wrapper but it has been found advantageous to provide perforations in the wrapper which may be reconciled with the records for ascertaining data about any print.

It has been found to be important to do the perforating while the wrapper is being run through the machine and before the cutting and wrapping operations. Many difficulties have been encountered in the perforation of the moving web due to the fact that the perforations were not smooth and even, the web often being ragged or the holes elongated and sometimes running into each other, so that the perforated symbols would be illegible and decipherable.

The object of this invention is to overcome these disadvantages and to provide a perforating device which will travel with the speed of the moving web and perform the perforating operation while the web is in motion.

Another object is to provide a perforating device which will properly perforate a moving web without tearing the web in any way or causing any elongation of the holes.

Another object is to provide a perforating device which is simple in construction, which can be readily and economically manufactured, and which can be quickly and easily installed on present butter wrapping machines.

The accompanying drawings illustrate a selected embodiment of the invention and the views therein are as follows:

Fig. 1 is a detail side view of a butter wrapping machine with the perforating device fixed thereon;

Fig. 2 is an elevation thereof; and

Figs. 3 and 4 are detail views of the cam for operating the device.

Referring to the drawings 1 represents the frame of a wrapping machine and it supports the drum shaft 2 for operating the machine. This shaft drives a gear 3 which drives the gear 4 on the cam shaft 5 through an intermediate gear 6. The lower end of the cam follower 7 is bifurcated as at 8 and it engages a block 9 which is loosely mounted on the cam shaft. A cam 10 fixed to the cam shaft 5 has a groove 11 formed therein to receive a roller 12 mounted on a cam roller stud 13 which is fixed to the cam follower. This arrangement of parts causes reciprocation of the cam follower, and the block causes perfect coordination of the parts and prevents any wear on the bifurcated end of the cam follower.

A lever 14 has its upper end pivoted to the frame at 15. A link 16 pivotally connects the cam follower to the lever 14 and a connecting link 14' pivotally connects the lever to the carriage 17. As the cam follower reciprocates the connecting parts cause the carriage to be reciprocated longitudinally of the frame.

Directly above the carriage is a head 18 provided with a plurality of holes 19 which are adapted to receive a plurality of pins 20 formed on the carriage for keeping the head and carriage in operative position relative to each other.

Shafts 21 and 22 are mounted in the frame

as clearly shown in Fig. 1. The shaft 21 has a bell crank 23 fixed thereon to which is connected the cam follower 24. The cam follower is slotted as at 25 and straddles the shaft as shown in Fig. 3. A cam roller 26 cooperates with a cam 27 which is similar in all respects to the cam 10. This arrangement of parts causes reciprocation of the cam follower and causes oscillation of the shaft 21 through the bell crank 23.

10 A link 28 is pivotally connected to the bell crank 23 and to a lever 29 fixed on the shaft 22. A bar 30 is connected to the shafts 21 and 22 by means of levers 31 so that oscillation of these shafts causes vertical reciprocation of the bar 30.

15 The head 18 carries rollers 32 and it is forced upwards by springs 33, Fig. 2, so that the rollers 32 are always pressing against the bar 30. As the bar moves downward the head is moved therewith and when the bar raises the springs 33 raise the head. This arrangement causes the head to move simultaneously with the bar.

20 The pins 20 are of sufficient length to maintain the head and carriage in operable relation to each other during the vertical reciprocation of the head.

25 In assembling the parts the carriage is positioned under the web 34 and the head above the web. The head is designed to receive a suitable punch 35 while the carriage carries a corresponding die 36.

30 The web 34 from the roll 37 supported by the machine frame, is threaded through the perforating device to the wrapping mechanism which cuts the web to suitable length and wraps it around the butter.

35 The operation of the device is as follows:— During rotation of the shaft 5 the carriage is reciprocated longitudinally due to the lever connections with the cam follower 7. The head is reciprocated vertically by the rod 30 which is operated by the cam follower 24 through the various levers, and by the springs 33.

40 The complementary pins 20 and holes 19 keep the head and carriage in operative relation with each other so that during longitudinal reciprocation of the carriage the head will be carried therewith. The head is free to move vertically, and during longitudinal reciprocation of the head and carriage the head is free to operate and punch the web. The levers, cams and followers are timed 45 properly so that the carriage may move with the web and substantially at the same speed.

45 From the description given it will be seen that a perforating device has been devised which will move with the moving web and when it attains the same speed as the web the perforation will be made in the moving web thereby assuring proper perforation of the web.

50 While the invention refers to a perforating device for butter machines it is to be un-

derstood that the device may be used on any machine of a like character or on any other machine for which the device may be adapted.

55 Changes may be made in form, construction and arrangement of the invention as set forth in the selected embodiment herein, without departing from the invention or sacrificing any of its material advantages, and the right is hereby reserved to make all such changes as fairly fall within the scope of the 60 following claims.

I claim:

1. A perforating device comprising a horizontally reciprocating carriage, a vertically reciprocating head in said carriage, horizontal bars on said carriage engaging the head and extending parallel with the line of movement of the web, means for vertically moving said bars in parallel relation to the web, and means for causing the head to reciprocate with the carriage.

2. In a perforating device of the class described, the combination of a frame, a carriage movable on the frame in parallel relation to the line of movement of the web, a perforating head on said carriage, horizontal bars engaging said head to move the head vertically, links pivotally connecting the bars with the frame to maintain said bars in parallel relation to the line of movement of the web, and means for actuating said links to move the bars vertically in parallel relation to the web.

3. In a perforating device of the class described, the combination of a frame, a carriage movable along the frame parallel to the line of movement of the web, an operating bar, a perforating head on the carriage in sliding engagement with the bar as the carriage moves, and means actuating said bar vertically in parallel relation to the line of movement of the web for vertically moving the perforating head.

4. In a perforating device of the class described, the combination of a frame, a carriage reciprocable along the frame in parallel relation to the movement of the web, a perforating head on the carriage reciprocable therewith and movable vertically towards and from the web, a pair of bars in engagement with the head and disposed in parallel relation to the movement of the carriage, links pivotally connecting said bars with the frame for vertically moving said bars in their parallel relation to the movement of the carriage, levers connected to said links for actuating the links, and a cam for actuating the levers.
